UNITED STATES PATENT OFFICE.

ANTHONY, J. SHAW, OF BRIDGETON, NEW JERSEY, ASSIGNOR OF ONE-THIRD TO JONATHAN B. PARKER AND ONE-THIRD TO DANIEL M. PARKER, OF BRIDGETON, NEW JERSEY.

GLASS-BLOWING MACHINERY.

No. 825,082.

Specification of Letters Patent.

Patented July 3, 1906.

Application filed November 22, 1905. Serial No. 288,526.

To all whom it may concern:

Be it known that I, ANTHONY J. SHAW, of Bridgeton, in the county of Cumberland and State of New Jersey, have invented certain 5 Improvements in Glass-Blowing Machines, of which the following is a specification.

This invention relates to certain improvements in machines for blowing bottles, jars, and analogous devices, as will hereinafter 10 fully appear.

In the description of the said invention which follows reference is made to the accompanying drawings, forming a part hereof, and in which—

15 Figure 1 is an exterior front elevation of the improved machine. Fig. 2 is an exterior side elevation. Fig. 3 is a section of Fig. 1, taken on the dotted line *z z* with certain parts thereof removed; and Fig. 4 is a front view of 20 a part of the machine.

Referring now to the drawings, 1 is the base of the machine, provided, as is usual, with wheels for the purpose of its easy removal from place to place. To the base 1 is 25 secured the fixed central column 2, to which is fastened the cam 3. This cam is best shown in Fig. 2, and it will be seen that it is provided with the inclined cam-face *a* and understood that there is a similar inclined 30 face on the opposite side. The upper and lower horizontal cam-faces are denoted, respectively, by *b* and *c*.

40 4 is a table resting in cam 3 and adapted to be rotated by hand about the fixed column 2 through the medium of the handles *d*. Upon the rotary table 4 are secured the bottle-molds 5, which in Fig. 3 are shown as six in number. These molds are commonly used in machines of this class, and each one consists of a base *e*, the hinged members *f*, which are provided with handles *g* for opening and closing the mold, a plate *h*, adapted to be slid by means of the handle *i* through a slot into the mold to form the bottom of the bottle or 45 jar, and the locking devices *j*, and I therefore make no claim to invention in the construction of the molds or the arrangement of the parts thereof relatively one with another. In connection with each mold, which is open at 50 the bottom, is a plunger 7, having a cavity in which a mass of molten glass is first made into

a hollow body. These plungers are also commonly in use and in themselves embody no part of my invention. No plunger is shown in Fig. 2, for the reason that only one mold is 55 illustrated in that figure and its plunger is within the mold. In Fig. 1 the lower portion of one of these plungers appears to the left of the figure.

The stems whereby an up-and-down movement is directly communicated to the plungers are represented by 9, and only one of these is shown in Fig. 2, while two of them appear in Fig. 1. The upper ends of the stems 9 are threaded, as at *k*, and screwed 60 into the lower ends of the plungers 7, so that a change in plungers to suit bottle-molds of different sizes may be made without disturbing the stems, and below the said threads there are formed on the stems slotted 65 enlargements 10 for the reception of certain operating-levers 12, hereinafter described. The lower ends of the stems 9 are internally threaded, and into them are screwed the externally-threaded ends *m*, whereby the stems 70 may be increased or diminished in length to admit of a change in the depth of the plunger. This adjustment is made still more complete by threading the anvil 13, (shown in position only in Fig. 2 and separately in Fig. 4,) upon 75 which each stem rests while the same is directly at the front of the machine, where the presser-man stands. The anvil is screwed 80 into the base 1.

Each one of the stems 9 is provided with a 85 lever 12, before briefly referred to, which is fulcrumed to a pendent lug 16, and one end of the lever is slotted and enters the slot in the enlargement 10 of the stem, to which it is connected by means of a pin *n*. The other end 90 of the lever carries a roller 17, which traverses the cam-faces of the cam, and the form of the cam-face is such that as each mold in the rotation of the table reaches the point *x*, Fig. 3, the stem carrying its plunger is suddenly 95 raised to its highest position within the mold and held thereat by the roller 17 traversing the horizontal face *c* at the bottom of the cam until the mold approaches the point *y*, where the stem and plunger fall to their lowest position and remain thereat until the point *x* is again reached.

The object of the anvil 13 is to furnish positive support for each plunger during the pressing operation, and to prevent the stems laterally striking the anvil as they come to the front of the machine the head of the anvil is extended toward the approaching stem and has its upper surface inclined, as shown in Fig. 4, so that the end *m* will easily mount the anvil.

10 The guides for the stems 9 consist of bored plates 19, held in position by the bolts 20 and the locking-nuts 22.

As in common with other machines of its class, the table 4 is required to have in intermittent rotation and be stopped as each mold in succession is brought to the front, and to effect accuracy in so placing the molds the upper surface of the table is provided with as many holes as there are molds, and 15 in connection with these holes there is a spring-held bar 24, adapted to slide in a suitable guide 25, bolted on the top of the base. To release the bar 24 from a hole in the table, its lower end is pivoted to a treadle 27, operated by the foot of the presser-man.

25 29 is a bracket on the central column 2. It is split at its end to the left in Fig. 2 and closed tightly on the column by means of bolts shown in that figure. The bracket 29 30 carries the pressing and blowing apparatus and their attachments, which will now be described.

30 35 40 45 50 55 60 65 70 75 80 85 90 95 100 105 110 115 120 125 30 is a vertical shaft adapted to have a vertical-reciprocating movement in the projecting end of the bracket 29, which at that point is split and fitted with bolts *a*, whereby loose motion may be taken up, as shown in Fig. 1. To the lower end of the vertical shaft 30 is removably attached the carrying-plate 32, having at its under face the follower 33, the lower portion of which is reduced in diameter, so as to fit into the upper part of the mold when the same is closed, and the end of the said shaft projects below the follower and forms a plunger which in the pressing operation first gives to the body of molten glass in the mold a hollow form.

35 40 45 50 55 60 65 70 75 80 85 90 95 100 105 110 115 120 125 35 is a horizontal shaft journaled in the bracket 29, having at each end a crank 37, and the crank to the right in Fig. 1 has a lateral extension 39 of any appropriate shape, to which a hand-lever 40 is screwed. A lock-nut *p* serves to prevent the unscrewing of the hand-lever.

55 60 65 70 75 80 85 90 95 100 105 110 115 120 125 55 The upper end of the vertical shaft 30 is threaded and extends through an interiorly-threaded nut 42, adapted to turn loosely in a cross-head 45. By turning the nut 42 independently of the cross-head the depth of penetration of the lower end of the shaft within the mold with a given movement of the actuating devices, as hereinafter described, may be easily regulated.

42 is a second cross-head, which is arranged

to slide vertically along but independently of 65 the movement of the shaft 30, and it is connected to the carrying-plate 32 by the pair of stems 49.

50 is a coiled spring on the vertical shaft 30, extending between the two cross-heads, 70 and its object is to give to the follower a yielding movement in the depression of the said shaft, and thereby effect the closing of the mold by the follower without respect to the degree of penetration of the lower end of the 75 shaft into the mold and the molten glass therein.

The devices whereby movement of the crank 37 is transmitted to the cross-head 45 consist of the links 52, which couple the ends 80 of the cross-head with the crank-pins.

In order that the vertical shaft 30 with its attachments may be yieldingly held in their highest position, the lateral extension of the crank 37 to the right in Fig. 1 is provided with a bar 53, carrying a weight 55, which overbalances the vertical shaft 30 and its attachments.

57 is a branched bracket extending from the central column, in the end of which the air-pipe is arranged to slide. The upper end of the pipe is provided with a seat suitable for connection to a flexible tube (not shown) leading to some source of air under pressure.

The lower end of the pipe 59 is made to 95 move longitudinally of and within a sleeve 60, having at its bottom a follower 62, which serves to tightly close an uncovered glass-charged mold when such is brought immediately beneath it. The movement of pipe 100 59 is communicated to the sleeve 60 by means of a coiled spring 63, the upper and lower ends of which are connected, respectively, to a collar 64, fastened to the said pipe and the top of the sleeve. This flexible connection 105 serves to take up part of the downward movement of the pipe in excess of that required to close the mold and at the same time effects a sufficient pressure of the follower on the surface of the mold with which it is brought in 110 contact to insure non-leakage of air in the blowing operation.

The air-pipe 59 is depressed in the downward motion of the vertical shaft 30 and its attachments by means of a triangular bracket 115 65, attached to the stem 49, which is shown to the left of Fig. 1. The outer end of the bracket 65 loosely grasps the said pipe and strikes the collar 67 on the pipe. This collar when the shaft 30 is elevated is considerably 120 below the operative end of the bracket 65, so as to take up the motion of the bracket which is in excess of that required to firmly place the follower 62 on the said mold, or that portion of the motion which is not allowed 125 for in the compression of the spring 63.

I have stated that the upper horizontal cam-face *b* will limit the extent of depression

of the stems 9; but the said surface need not be utilized, as the enlargements 10 of the said stems may answer the purpose of stops by coming in contact with and resting upon the

5 guide-plates 19, as shown in Fig. 1, and, indeed, this latter arrangement is the preferred one, as the said guide-plates are vertically alterable in position on the bolts 20 which sustain them.

10 Supposing the various parts of the machine to be in the positions illustrated in Figs. 1 and 2 of the drawings and the presser-man to be standing in front of the machine, the gathering-boy holds a mass of molten glass over the

15 mold immediately to the right of the presser-man, who clips it from the gathering-rod and allows the glass to fall to the locked mold beneath. The presser-man then turns the

20 table to the left until the charged mold is directly in front of him, when the table is automatically locked. The presser-man then draws down the lever 40, when the vertical shaft 30 and its follower 32 descend together until the mold is tightly closed by the follower.

25 The vertical shaft then descends alone, the spring 50 being compressed in the operation, and its end enters the glass contained in the plunger and forms a cavity therein. The presser-man then releases the hand-lever,

30 which rises with the vertical shaft 30 and its follower 32, and turns the table to the left, when the roller 17 of the lever 12 by ascending the inclined portion *a* of the cam-face effects the lowering of the plunger in the mold.

35 Before the mold reaches the second position the plate *h*, which forms the bottom of the bottle or jar, is pushed inward, so as to close the open bottom of the mold. When the mold has reached the second position and the

40 table has stopped, a similar pressing operation is performed with respect to the mold to the right of the one just referred to, and at the same time the follower 62 descends to and closes the first mold, and compressed air be-

45 ing admitted to the pipe 59 the bottle or jar is blown. Before the roller 17 of the lever 12 belonging to the first mold reaches the other or second inclined cam-face the mold is opened by an attendant and the completed

50 bottle or jar taken out, the supply of compressed air having been automatically stopped. The mold is then closed and the plate *h* withdrawn to its original position, when the mold is ready for a second charge of

55 molten glass. I have described the operation of making one bottle; but this operation is the same with each mold successively, a stop in the motion of the table being had as each mold comes to the front of the machine

60 and opposite the presser-man:

I have not described the appliances whereby air is automatically admitted from the air-pipe to the mold, for the reason that such ap-

pliances are commonly used in machines of this class and they form no part of my invention.

65 I claim as my invention—

1. In a glass-blowing machine, the combination of a fixed central column, a table adapted to rotate about the column, a fixed cam situated beneath the table, a series of molds placed on the table, each mold having a vertically-moving plunger-carrying stem which is adjustable in length and a cross-lever, one end of which is connected directly with the stem, and the other adapted to engage the cam, and a fixed anvil over which each stem is successively brought in the rotation of the table, to receive and stop the stems, independently of the action of the cam, substantially as specified.

2. In a glass-blowing machine, the combination of a fixed central column, a table adapted to rotate about the column, a fixed cam situated beneath the table, a series of 85 molds placed on the table, each mold having a vertically-moving plunger-carrying stem which is adjustable in length and a cross-lever one end of which is connected directly with the stem and the other adapted to engage the cam, and a fixed anvil over which each stem is successively brought in the rotation of the table, to receive and stop the stems, independently of the cam, the said anvil being alterable in height, substantially as 90 specified.

3. In a glass-blowing machine, the combination of a fixed central column, a table adapted to rotate about the column, a series of molds supported by the table, a cam situated beneath the table, the said molds having each a vertically-moving plunger-carrying stem adjustable in length and a lever through which the vertical movement of the stem is received from the cam, and a stop-plate alterable in height with which a part of the stem comes in contact as the stem reaches its lowest position, substantially as specified.

4. In a glass-blowing machine, the combination of a fixed central column, a table 110 adapted to rotate about the said column, a series of molds supported by the table, a cam situated beneath the table, the said molds having each a vertically-moving plunger-carrying stem adjustable in length provided 115 with an enlargement and a lever through which the vertical movement of the stem is received from the cam, and a stop-plate alterable in height with which a portion of the stem comes in contact as the stem reaches its 120 lowest position, substantially as specified.

5. In a glass-blowing machine, a fixed central column, a table adapted to rotate about the column, a series of molds carried by the table, combined with two brackets secured to 125 the said column, one bracket supporting the

glass-pressing devices, and the other, the glass-blowing appliance, means whereby the downward movement of the said blowing appliances is effected directly from the pressing devices, and compensating mechanism whereby the movement of the said pressing devices, which is in excess of that of the blowing ap-

pliances, is taken up, substantially as specified.

ANTHONY J. SHAW.
